United States Patent Office

Des. 232,766
Patented Sept. 10, 1974

232,766

CLOCK-RADIO

John T. Houlihan, Manlius, N.Y., assignor to
General Electric Company

Filed Dec. 22, 1972, Ser. No. 317,675

Term of patent 14 years

Int. Cl. D10—01

U.S. Cl. D56—4 B

FIG.1.

FIG.2.

FIG.3.

FIG.4.

FIG.5.

FIG.6.

FIG. 1 is a front elevational view of a clock-radio showing my new design;

FIG. 2 is a top plan view thereof;

FIG. 3 is a bottom plan view thereof;

FIG. 4 is a rear elevational view thereof;

FIG. 5 is a right side elevational view thereof;

FIG. 6 is a left side elevational view thereof.

I claim:

The ornamental design for a clock-radio, as shown.
